PAPER CHUTE FOR ACCOUNTING MACHINE
RECORD STRIPS

Pascal Spurlino, Jacob Gantner, and Walter J. Kreider, Dayton, Ohio, assignors to The National Cash Register Company, Dayton, Ohio, a corporation of Maryland

Application November 10, 1945, Serial No. 627,850

8 Claims. (Cl. 271—2.1)

1

This invention relates to accounting machines, and particularly to machines adapted for use in banks, especially in the proof departments thereof, where the various items are listed and distributed for a proof balance at the end of each day.

This invention is also adapted for use in machines used in business houses of various types where analysis breakdowns of the several items of various departments are desirable.

The invention is adapted to be embodied in machines of the general type shown in the following United States Letters Patent Nos. 1,619,796; 1,747,397; and 1,761,542, issued March 1, 1927; February 18, 1930; and June 3, 1930, respectively, to Bernis M. Shipley; No. 2,175,236, issued October 10, 1939, to Maximilian M. Goldberg; No. 2,141,332, issued December 27, 1938, to Charles H. Arnold, No. 1,693,279, issued November 27, 1928, to Walter J. Kreider; and No. 2,305,000, issued December 15, 1942, to Mayo A. Goodbar; and reference may be had to said patents for a complete illustration and description of such general types of machines. A more specific type of machine in which the invention is embodied is shown in United States Letters Patent No. 2,361,662, issued October 31, 1944, to Pascal Spurlino and Konrad Rauch.

This latter Patent No. 2,361,662 shows a machine having seven individual audit, classification, or listing tapes or strips, each carried by a removable frame adapted to be slid into and out of the machine and having an interlocking means associated with the machine releasing mechanism to prevent operation of the latter unless all seven of the tape carrying frames are latched in their proper positions in the machine.

In that machine, as each tape is printed upon and fed forwardly past the serrated tear-off plate, the free end of the tape, guided by a curved guide, is automatically coiled up within the unit. This guide is secured to the cover of the unit, and, when the operator wishes to tear off the printed coil of the tape, the cover is swung downwardly, it being hinged at the bottom, and the operator pulls the coiled end of the tape out of the space within the curved guide and then tears this coiled end off of the tape by means of the tear-off plate.

Sometimes, especially when a large number of items has been printed on the tape, the coil of tape is much larger than normal and consequently more difficult to remove from the cover and curved guide, and the paper is often torn during such removal.

2

Such conditions are eliminated by the present invention, which has for one of its objects the provision of a combined slideable paper chute and cover whereby the free end of the tape is guided in a comparatively large arc, terminating in a straight line beneath the carrying frame, which carrying frame, except for the hinged cover, is substantially like that shown in said United States Patent No. 2,361,662.

10 Another object is to provide a novel slideable paper chute and cover for a tape feeding mechanism, the chute having means to prevent accidental removal of the same from the machine. Another object is to provide a removable tape carrying frame having a tape feeding means with a combined cover and paper chute to guide the free end of the printed tape down and beneath the carrying frame.

Another object is to provide a slideable combined cover and paper chute for a tape feeding means to guide the tape when the cover is closed, and adapted to be slid forwardly to expose a portion of the tape to facilitate inspection of printed items thereon, and at the same time make it easy for the operator to tear off the tape when desirable.

With these and incidental objects in view, the invention includes certain novel features of construction and combinations of parts, the essential elements of which are set forth in appended claims, and a preferred form or embodiment of which is hereinafter described with reference to the drawings which accompany and form a part of this specification.

35 In said drawings:

Fig. 1 is a side elevation of a portion of a tape carrying frame, tape feeding means, and a slideable combined cover and paper or strip chute.

Fig. 2 is a plan view showing the relation between the cover and paper chute and the tape guide plate of the carrying frame, showing how the guide plate acts as a locating means for the cover and chute.

Fig. 3 is a view looking from the rear, showing the relation between the cover and strip chute and the tape guide plate.

Fig. 4 is a detail view of a portion of the means for controlling the release of the machine if the tape should break or become exhausted.

Fig. 5 is an enlarged fragmentary view of a portion of the combined cover and strip chute and the means thereon to prevent accidental complete removal from the machine.

55 Fig. 6 is a front elevation of the strip carrying

frame, the combined cover and strip chute, and the front support guide for the chute.

Fig. 7 is a section on line 7—7 of Fig. 1, looking in the direction of the arrows, and shows the rear support guide for the chute.

Fig. 8 is a section on line 8—8 of Fig. 1, looking in the direction of the arrows, and shows the mounting of the tape carrying frame.

Fig. 9 is a top plan view showing three units of tape carrying frames and combined covers and strip chutes, with the center cover and chute drawn out forwardly so that the tape may be drawn completely out of the cover and strip chute and torn off on the serrated edge of the tear-off plate.

Fig. 10 is a plan view of the tape carrying frame showing the mounting for the supply roll of tape, the frame latch, and a part of the means for locking the machine release when the tape supply roll is exhausted or if the tape should break.

Fig. 11 is a side elevation on a reduced scale, showing the cover chute drawn out.

Fig. 12 is a side elevation in reduced scale, showing the cover and strip chute in normal position.

General description

This invention includes a novel combined cover and paper chute for each of a plurality of removable tape carrying frames, such as shown in the Spurlino and Rauch Patent No. 2,361,662, above mentioned, which cover and chute replaces the hinged cover in which the free end of the tape is coiled.

The present combined cover and strip chute is slidably mounted in a rear support guide and a front support guide and when in position engages locating flanges of a lip on the tape guide plate over which the free end of the tape passes after leaving the feed roll.

Means is provided on the combined cover and strip chute to prevent its accidental complete removal from the machine, such means comprising a stop member on the bottom of the cover chute, which contacts the rear side of the front support guide, thus limiting the forward sliding movement of the combined cover and strip chute.

These combined cover and paper chutes extend rearwardly to substantially the rear edge of the machine, and thus on long analysis runs the free ends of the tapes come out of the chutes at the back of the machine.

A protective shield encases all of the paper chutes to protect the operator's knees and also to prevent the operator from accidentally pushing the chutes out of place.

A hole is provided in the shield beneath each chute so that the stop thereon may be flexed upwardly, by the operator, out of stopping position when it is desired to completely remove the cover and strip chute from the machine. When in normal position, each cover chute is latched by a spring retaining latch, and to remove or slide the cover and strip chute the operator merely pulls on the knob on the cover and the retaining latch is cammed out of retaining position. When the cover and strip chute is pushed back into its operative position, the spring retaining latch snaps back into its retaining position.

Detailed description

Since the individual tape carrying frame and the combined cover and strip chute for each frame, and the tape feeding means are all alike, a description of one unit comprising said mechanism will suffice for all.

The tape carrying frame and tape feeding means will be but briefly described, since the feeding means and the frame, except the new combined cover and paper chute, are substantially the same as illustrated and described in the above-mentioned Spurlino and Rauch Patent No. 2,361,662, which may be referred to for a complete illustration and description of the frame and tape feeding means.

The several tape carrying frames are supported on a base plate 20 (Figs. 1 and 8) secured to the bottom of frames 21 (only one being shown), which frames 21 support the main printing mechanism of the type of machine shown in said Spurlino and Rauch patent just above mentioned. The base plate 20 has secured to the top thereof a U-shaped member or channel 22, having guide flanges 23 to cooperate with the tape carrying frame. There is one channel 22 for each tape carrying frame, and in this application three frames are shown. This number may vary according to the needs of the business for which the machine is made. Each frame has sides 24 and 25 tied together near their lower edges by tie rods 27 and 28 and a tie bar 29, and near their upper edges by tie rods 30, 31, 32, and 33. The rod 27 and the bar 29 rest on the tops of the flanges 23, and studs 35, carried by the sides 24 and 25, ride beneath the flanges 23. The sides 24 and 25 also have flanges 36 and 37, respectively, which ride beneath the flanges 23. Therefore, the listing tape frame is kept from any lateral movement and also from any up-and-down movement, the flanges 36 and 37 preventing lateral movement and also preventing any movement of the frames too far in an upward direction.

Pivoted on a stud 39 on the side 25 (Fig. 10) is a spring-actuated latch 40 adapted to latch over a tie bar 41 (Fig. 1) when the frame is properly located in its operating position in the machine. This tie bar 41 connects the printer frames 21, as shown in the above-mentioned Spurlino and Rauch patent, which also shows a latch identical with the latch 40.

To remove the listing tape frame from the machine, the operator merely depresses the forward end of the latch 40 to release it from the tie bar 41, whereupon the entire frame may be withdrawn from the machine after the combined cover and paper chute has been first removed.

A listing tape 44 is fed from a supply roll 45 (Figs. 1 and 9), which is supported on a trunnion 46, projecting from the stud 39, and a trunnion 47 carried by a spring arm 48 secured to the side 24.

From the supply roll 45 the tape 44 is fed upwardly over a roller 50, which is supported by a guide plate 51 secured to the sides 24 and 25 of the tape frame. The tape 44 is then fed upwardly over a roller 52 on the stud 30 and rearwardly over a roller 53 on the stud 31, thence around a roller 54 on the stud 32, and then forwardly between a feed roller 55 and a tension roller 56.

The feed roller 55 is adapted to be rotated counter-clockwise by means to be hereinafter described, so as to feed the free end of the tape 44 downwardly between a tape guide plate 57 and a tear-off strip 58, and into the mouth of a combined cover and tape chute 60, to be later described.

70 *Individual tape feeding mechanism*
As previously stated, the tape 44 is fed between the feed roll 55 and the tension roll 56 (Fig. 1). Connected by a hub 61 to the feed roll 55 is a ratchet 62. Pivoted on the rod 33 is an arm

63 carrying a spring-pressed feeding pawl 64, cooperating with the ratchet 62. Pivoted at 65 to the arm 63 is a link 66, slidably supported by a slot 67, on a stud 68 carried by the side 24. A spring 69 holds the link 66 with the right end wall of the slot 67 contacting the stud 68 when the parts are in their normal positions. A retaining pawl 10 supported by the side 24 cooperates with the ratchet 62 to prevent any retrograde movement of the ratchet.

The link 66 carries a stud 71 adapted to be engaged by a slot 72 in the forward end of a link 73, which is pivoted at 74 to an arm 75, fast on a shaft 76, which shaft is supported by the printer frames 21. A link 77 is connected to the arm 75 and to a bell crank 78, which is pivoted on a shaft 79, also supported by the frames 21. The bell crank 78 carries rollers 80 and 81, cooperating with plates 82 and 83, respectively, of a double plate cam secured to a printer drive shaft 84, which receives one clockwise rotation during each operation of the machine by means fully illustrated and described in the above-mentioned Spurlino and Rauch Patent No. 2,361,662.

As above stated, the notch 72 of the link 73 is normally disconnected from the stud 71, but by means which will be briefly described, when one of the individual listing tapes is selected for operation, the link 73 is permitted to rock counter-clockwise around its pivot 74, whereupon the notch 72 engages the stud 71. During an operation of the machine, the cams 82 and 83 rock the arm 75 first clockwise and then counter-clockwise to normal position. When the link 73 is engaged with the stud 71, the clockwise movement of the arm 75 draws the link 66 to the right (Fig. 1), which rocks the arm 63 and causes the pawl 64 to turn the ratchet 62 and the feed roll 55 to feed the listing tape 44 after the printing has taken place thereon. Such printing on the tape 44 is accomplished by means of type wheels 85, which are set and actuated by means shown and mentioned in the above-mentioned Spurlino and Rauch patent, after which impression means (not shown herein but fully shown and described in the said Spurlino and Rauch patent) is operated to make a legible printing impression from the type wheels 85 upon the selected tape 44.

There is only one pair of cams 82 and 83, one bell crank 78, one link 77, for all of the individual listing tapes 44. However, there is an arm 75 associated with each of the listing tapes 44 in the machine.

As only one of the listing tapes is selected for operation at a time, it is necessary to select which one of the tapes shall be printed upon and which one of the tape feeding mechanisms will be operated for each operation of the machine. This means is all fully illustrated and described in the above-mentioned Spurlino and Rauch patent. When the particular tape is selected, the arm 73 is rocked counter-clockwise as above mentioned, by means of an arm 86, which is selectively controlled to rock in a counter-clockwise direction. This arm 86 carries a stud 87 engaging a slot 88 in the arm 73, thus rocking the arm 73 counter-clockwise to engage its notch 72 with the stud 71.

All of such selection mechanism is fully illustrated and described in the above-mentioned Spurlino and Rauch patent.

There is means herein shown to prevent the machine releasing mechanism from functioning if there should be no tape 44 in the machine, or should the tape be ruptured for any reason at all. This mechanism will now be described.

The machine releasing mechanism per se is not shown in this application but is fully illustrated and described in the above-mentioned Spurlino and Rauch patent. Cooperating with that mechanism is an arm 101 (Fig. 1) having a spring 102 normally holding the arm in contact with a stud 103 on a slide 104, slidably mounted on the tie bar 29 and a shaft 105 supported by the sides 24 and 25 of the tape carrying frame.

10 Pivoted on this shaft 105 is an arm 106 (Figs. 1 and 4), which is engaged by the feed link 66. Also secured to the arm 106 by a hub 107 is an arm 108 held in contact with a stud 109 by a spring 110 stretched between the stud 109 and a stud 111 on the arm 108. The stud 109 is carried by an arm 112 pivoted on the shaft 105 and secured to an arm 113 having a bayonet slot 114 into which projects a pin 115 on the slide 104. The slide 104 also carries a pin 116 engaging a slot 117 in an arm 118 pivoted on the shaft 105. The arm 118 has a flange 119 (Figs. 1 and 10) engaging the tape 44 opposite an opening 120 in the guide plates 51.

20 Normally, with the parts in the positions shown in Fig. 1 when the link 66 is moved to the right to feed the tape 44, the arm 106, and the arm 108 are rocked clockwise, whereupon the spring 110 rocks the arm 112 and the arm 113 and causes the vertical portion of the bayonet slot 114 to engage the stud 115 on the slide 104. Therefore the stud 103 maintains the arm 101 in the position shown, in which position the machine releasing mechanism (not shown) is free to be operated.

25 However, should the supply roll 45 become exhausted or should the tape 44 break, so that there is no tape 44 between the flange 119 and the opening 120, then the spring 102 will rock the arm 101 in a clockwise direction, which through the mechanism shown in the Spurlino and Rauch patent will prevent release of the machine for a subsequent operation. At the same time, this clockwise movement of the arm 101, through its engagement with the stud 103, moves the slide 104 to the left, causing the pin 115 to engage the horizontal portion of the bayonet slot 114, which prevents any clockwise movement of the arms 113 and 112.

30 35 40 45 50 55 Should the arm 118 be permitted to rock counterclockwise during an operation due to failure of paper between the flange 119 and the opening 120, thus causing the locking of the arms 112 and 113, the flexible connection between the arms 108 and 112 permits the arm 106 to be rocked while the feeding link completes its movement during such operation.

Combined cover and tape chute

60 The cover and tape or strip chute 60 is rectangular in shape, and shown in section in Fig. 7, the front and bottom being solid and the back and top being open. At the top the cover and strip chute 60 (Figs. 1 to 3) is flared to form a mouth 131, and the opening in the back of the mouth is widened as at 132. This wider opening 65 132 engages ears 133 on a lip 134 of the tape guide plate 57, so that when said chute 60 is in its normal position, shown in Fig. 1, the ears 133 provide a locating means for the chute 60.

65 70 75 The cover and strip chute is supported near its front end by a guide support 135, (Fig. 5) secured to the bottom of the plate 20. This guide 135 extends across in front of all of the tape printing units and is provided with slots 136 (Fig. 6), there being one slot for each of said chutes 60. Near the back of the cover and strip chute 60 there

is a rear guide 140 secured to the bottom of the usual wood base 141. This guide 140 is provided with slots 142, one for each of the cover and strip chutes 60, as shown in Fig. 6. A shield 143, formed with a bottom 144 and sides 145 (only one of which is shown), has flanges 146, by means of which the shield 143 is fastened to the bottom of the plates 20. The shield 143 has a flange 147 extending upwardly from the base 144 and by means of this flange 147 the shield 143 is secured to the front guide 135.

This shield 143 extends across and underneath all the chutes 60 to prevent said chutes from being moved out of position by the operator when sitting at the machine.

Secured to the bottom of the cover and strip chute 60 is a stop plate 150, which is for the purpose of preventing the chute 60 from being accidentally withdrawn from the machine. When the cover and strip chute 60 is drawn forwardly (to the left as viewed in Fig. 1), the left end of the stop plate 150 contacts the rear side of the guide 135, as shown in Fig. 5, and prevents the chute 60 from being fully withdrawn from the machine.

To permit the operator to fully withdraw the cover and strip chute 60 from the machine, the bottom 144 of the shield 143 is provided with openings 151 beneath each of said chutes 60 and the operator may, by putting his finger through this hole 151 and pressing the stop plate 150 upwardly until the front end of the same is in line with the slot 136, fully and completely withdraw the chute 60 from the machine.

To assist in drawing the cover and strip chute 60 out of the machine, the front part of the cover and strip chute has secured thereto a curved plate 152, having integral therewith a hand pull or knob 153.

To latch the cover and strip chute 60 in position, there is secured to the front of each chute a plate 154 having bent-up ears 155, one of each side of said chute 60, to support a stud 156. Pivoted on this stud 156 is a pair of latches 157, connected to operate in unison by a yoke 158. A torsion spring 159 wound around the stud 156 and engaging one of the latches 157 causes the pair of latches 157 to be held in engagement with a rod 160, which is supported by the front sides of the channels 22 and extends across all of the printing units.

To draw the cover and stop chute 60 outwardly, to inspect the printed tape 44 or to tear off the printed portion thereof, the operator merely grasps the knob 153 and pulls toward the left as viewed in Fig. 1, whereupon the latches 157 are cammed off the rod 160.

When the cover and strip chute 60 is pushed back into normal position again, the latches 157 are rocked counter-clockwise against the action of the spring 159 until the chute is in the position shown in Fig. 1, whereupon the spring 159 causes the latches 157 to engage the rod 160 to retain the chute in its operative position.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. A chute for guiding record material; said chute being curved at one end and terminating in a relatively long straight portion and being

made of a single piece of material and substantially rectangular in cross section and having an opening the full length of the top of the straight portion and the back of the curved portion, said opening being wider at the curved end of the chute which is flared at said curved end to increase its internal area to form a mouth for the reception of the leading end of record material; said chute having a spring actuated latching yoke adjacent its curved end adapted to engage means mounted independently of said chute, said chute also having a flexible stopping member secured to the bottom of the straight portion of said chute and adapted to cooperate with a stationary member beneath said chute but mounted free of said chute.

2. An insertable combined cover and guiding chute for record material for a record strip carrier having strip feeding means, said chute when inserted into its operative position relative to said carrier, acting as a cover for a portion of the front of the carrier; said chute being curved at the cover end thereof and terminating into a relatively long strip chute extending beneath the carrier, said chute being flared at the terminus of its curved end to receive the leading end of the record material as it is fed from the carrier, said chute being provided with a spring actuated latching means which, when the chute is inserted into its operative position, snaps over stationary means on the carrier base to retain the chute in its operative position.

3. In a machine of the class described, the combination of an insertable record strip carrier; strip feeding means carried by said carrier; a guide member carried by said carrier to guide the free end of the strip when said strip is fed; and an insertable combined carrier cover and strip chute, said chute being adapted to cover a portion of the front of the strip carrier when said chute and carrier are inserted in the machine, said chute being further adapted to engage said guide member in a position to receive the free end of the strip after it is fed past the guide member to direct the free end of the strip downwardly and rearwardly in front of and beneath the record strip carrier.

4. In a machine of the class described, the combination of an insertable record strip carrier; a stationary guiding device for said carrier to guide the latter upon its insertion into the machine; a strip feeding means carried by said carrier; a guide member carried by said carrier to guide the free end of the strip when said strip is fed; an insertable combined carrier cover and strip chute, said chute being adapted to cover a portion of the front of the strip carrier when said chute and carrier are inserted in the machine, said chute being further adapted to operatively engage the strip guide member in a position to receive the free end of the strip after it is fed past the strip guide member to direct the free end of the strip downwardly and rearwardly in front of and beneath the record strip carrier; stationary means carried by said device; and latching means carried by the front portion of said combined carrier cover and strip chute and adapted to snap into latching engagement with said stationary means when the chute is inserted to retain said chute in operative position in the machine.

5. In a machine of the class described, the combination of an insertable record strip carrier; a guiding device for said carrier to guide the latter upon its insertion into the machine;

strip feeding means carried by said carrier; a guide member carried by said carrier to guide the free end of the strip when said strip is fed; an insertable combined carrier cover and strip chute, said chute being adapted to cover a portion of the front of the strip carrier when said chute and carrier are inserted in the machine, said chute being further adapted to operatively engage the strip guide member in a position to receive the free end of the strip after it is fed past the strip guide member to direct the free end of the strip downwardly and rearwardly in front of and beneath the record strip carrier; stationary means carried by said device; a spring-operated latching means carried by said combined cover and strip chute and adapted to snap into latching engagement with said stationary means upon insertion of the chute to retain said chute in operative position in the machine; a front guide support secured to said device to guide and support said cover and strip chute during and after insertion of said chute into the machine; a rear guide support secured to the base of the machine to guide and support said cover and strip chute during and after insertion of said chute into the machine; and means carried by the cover and strip chute and adapted to cooperate with said front guide support to prevent accidental complete withdrawal of the cover and strip chute from the machine.

6. In a machine of the class described, the combination of an insertable record strip carrier; strip feeding means carried by said carrier; an insertable carrier cover and strip chute to receive the free end of the strip when it is fed after insertion of said carrier and said chute into the machine, said chute having an opening in the back and top sides thereof; and a guide member carried by said carrier to guide the free end of the strip, said guide member having means thereon projecting at right angles to the plane of the guiding surface of the guide member to engage the opening in said chute upon insertion of the chute in the machine after insertion of said carrier in the machine to control the entry of the free end of the strip into said chute after said strip is fed.

7. In a machine of the class described, the combination of an insertable record strip carrier having record strip feeding means; an in-

sertable strip chute for the record strip to guide the free end of the strip downwardly in front of and rearwardly beneath said strip carrier, said strip chute being formed in one single piece having an opening the entire length thereof in the rear side and top side, and having an enlarged end to receive the free end of the record strip, said opening being enlarged adjacent the enlarged end of the strip chute; a member carried by the record strip carrier intermediate the feeding means and the strip chute; and projections on said member to engage the enlarged portion of said opening upon insertion of said strip chute to align the strip chute with said member.

8. A chute for guiding record material, said chute being curved at one end and terminating in a relatively long straight portion and being made of a single piece of material and substantially rectangular in cross section, but having an opening the full length of the top of the straight portion and the back of the curved portion, said opening being wider at the curved end of the chute, which is flared at said curved end to form a mouth; a spring-actuated latch device carried by the front portion of said chute adapted to cooperate with an immovable means independent of the chute to retain the chute in proper guiding position relative to the lead end of the record material; a hand pull secured to the front of the curved portion of the chute; and a flexible stop means secured to the bottom of the straight portion of the chute and adapted to cooperate with a stationary member to limit the forward movement of the chute when it is so moved by the hand pull.
